AIR SWEPT PULVERIZER FOR USE IN
CLOSED-CIRCUIT PULVERIZED MA-
TERIAL TRANSPORT SYSTEMSRalph M. Hardgrove, Westfield, N. J., assignor to
The Babcock & Wilcox Company, Rockleigh,
N. J., a corporation of New Jersey

Application December 11, 1943, Serial No. 513,841

10 Claims. (Cl. 241—48)

1 The invention herein disclosed relates to a pulverizing apparatus especially adapted for use in a system wherein pulverized products are transported from the apparatus by means of a current of air or other suitable gaseous carrier medium, and varying proportions of such products are returned to the apparatus for recycling. The apparatus and system will be found suitable for use with materials of various composition including, for example, such solids as coal, mineral ores, cement clinker, or other solids of similar physical characteristics.

The invention may be usefully applied in a pulverized fuel firing system wherein pulverized coal is discharged from the pulverizer in a stream of carrier air, and the resulting fluent mixture delivered to a burner, or to a number of burners, with any surplus quantity of the mixture being returned to the pulverizer to provide continuous circulation. In such a system, provision is made for feeding raw coal to the pulverizer at rates sufficient to replace the amounts taken by the burner or burners, and for supplying fresh or make-up air to the pulverizer at rates sufficient to maintain a current of air therethrough at all loads while providing an output mixture having the particular fuel-to-air ratio desired for any given load.

In certain types of pulverizers wherein grinding elements are relatively rotatable about a vertical axis, the coal and make-up air are conveniently supplied to the pulverizing zone from opposite sides, that is, the raw coal being fed from the upper side for discharge by gravity into the zone, and the fresh air being supplied from the under side for admission to the zone in an annular stream. Since the fuel-air mixture is fluent in character, any surplus of the mixture to be returned to the pulverizer may be mingled with the incoming supply of make-up air, prior to admission of the air to the grinding zone, thereby producing a carrier medium of modified density which may be admitted to the grinding zone through the passage or passages normally provided for the fresh air alone.

Under normal operating conditions, the coal and air are supplied to the pulverizer in such proportions that the resulting output mixture contains a smaller quantity of air than is necessary for complete combustion; thus, the mixture with its normal content of primary air may be transported from the pulverizer without risk of premature combustion or explosion, and the required amount of secondary air may be added

2 at the burners to provide a suitably combustible mixture.

When a surplus of the mixture is returned to the pulverizer, as in the circulating system herein disclosed, the fuel and air content of the returning mixture remains essentially the same as when originally discharged from the pulverizer, a relatively high velocity of flow being maintained throughout the return conduit system to prevent any appreciable quantity of pulverized coal from settling out of the returning stream. When the return mixture and the make-up or primary air are combined for flow through the grinding zone, the proportion of air in the resulting mixture is appreciably higher than in the returning fuel air mixture, thereby tending to provide an atmosphere capable of supporting combustion of the entrained coal particles. It is considered important therefore to avoid any condition which might lead to ignition of such a mixture to cause a possible explosion, either through the coking of pulverized coal accumulations in or adjacent the zone of mixing, or as a result of hot coke particles being carried into the mixing zone and allowed to accumulate therein. When a heated supply of primary air is employed, the hazard of the mixture becoming ignited is somewhat increased, due to a certain amount of heat being retained in the returning coal-air mixture which would tend to promote coke formation.

It is a purpose of the invention therefore to maintain the fluid flow passages leading to the grinding zone clear of all coal or coke accumulations, and to cause the make-up air and the returning coal and air to be mixed in a zone where there is the least tendency for coal or coke to collect.

An additional object is to maintain fluid flow velocity conditions in and adjacent the mixing zone of a character maintaining the adjoining passages clear of any pulverized coal or coke that might tend to settle therein; in general, the velocities for the make-up air being subject to variation over a considerable range, while the velocities for the dust-laden stream are maintained more nearly constant.

Another object is to cause the respective streams to enter the mixing zone in such directions and at such velocities as to promote thorough mingling of the streams throughout the zone.

A further object is to provide a mixing zone having an outlet direct to the grinding zone or adjoining region where the issuing stream will

pick up additional coal particles, which being moist, reduce the temperature abruptly, thereby increasing the proportion of coal to air in the mixture and providing a relatively non-explosive mixture for flow through and from the pulverizer, the area of flow from the mixing zone into the grinding zone to be small enough to maintain flow velocities at least as high as the velocities prevailing within the mixing zone, and higher than the rate of flame propagation for the fuel and air mixture in transit at that location.

Among other objects, it is proposed to maintain the passages leading to and from the mixing zone clear of oversize particles or other foreign materials which might tend to obstruct the flow of air and pulverized coal.

More specific objects include the admission of coal-free air and coal-laden air to the pulverizer through concentrically arranged inlet areas; the mixing of both bodies of air in an annular zone closely adjacent the grinding zone; and the admission of both bodies of air to the pulverizer in the same direction, with subsequent reversal of flow of one body of air for mixing in a surrounding annular zone.

The foregoing objects and others not specifically mentioned are more fully set forth in the description to follow, together with various advantageous features of construction as illustrated in the accompanying drawings, in which:

Fig. 1 is a layout, in plan, of a pulverized coal circulating system embodying apparatus of my invention;

Fig. 2 is a sectional assembly of the pulverizer included in the system of Fig. 1;

Figs. 3 and 4 are plan sections of the pulverizer assembly shown in Fig. 2, taken along lines 3—3 and 4—4 respectively; and

Fig. 5 is an enlarged fragmentary outline of parts shown in Figs. 2 and 3.

The system according to Fig. 1 of the drawings includes an air swept pulverizer 10 arranged to supply pulverized coal and primary air to burners 12 and 14 associated with a form of metallurgical furnace 16, here indicated as a billet heating furnace, although as will be understood, other types of furnaces may be employed and, if desired, the burners arranged for firing separate furnaces.

The pulverizer 10 is shown as being located adjacent the charging end 18 of the furnace 16 and its output of pulverized coal and primary air is discharged through pipe 20 to the inlet of an exhauster fan 22 from which the mixture is delivered to a main distributor conduit 24 at its inlet end 26, the opposite end or return length 28 of the conduit being connected to the air inlet side of the pulverizer to form a closed circuit or loop as will be explained more in detail hereinafter. The pulverizer and fan are conveniently operated by a single motor 30.

The loop conduit 24 is tapped at successive positions along its length to supply a mixture of pulverized coal and air to any one of the burners, or group of burners, that it may be desired to maintain in operation; the burners 12 along one side of the furnace being supplied through burner lines 32 leading from the conduit 24, the larger burners 14 at the discharging end of the furnace remote from the location of the pulverizer being supplied through burner lines 34, and the remaining side burners 12 through additional burner lines 32. Suitable valves, not shown, may be installed in each of the burner lines 32 and 34 to positively cut off the supply of fuel and primary

air to any burner not in operation; and to regulate the supply of fuel to the various burners during operation. Any surplus quantity of the total pulverizer output above that diverted to the burner or burners in operation is returned to the inlet side of the pulverizer 10 for recycling in view of the looped arrangement of the conduit 24 which provides a closed circulatory system. A secondary supply of air may be admitted to the burners or to the furnace or furnaces for complete combustion of the fuel, but the details of such secondary supply are not included in the present invention, and further disclosure is therefore considered unnecessary.

The references to coal as the material being pulverized, and to air as the carrier medium, are not to be taken literally, but are to be interpreted as embracing other solids, combustible or otherwise, and other gaseous media, capable of adaptation to the system described. In a broad sense also, the burners 12 and 14 become selected points of delivery or use, for example, bins or other containers, irrespective of whether the material transported is a fuel or is a material of non-combustible character.

Referring to Fig. 2, the pulverizer 10 is, by way of example, of a known ball-mill type having its grinding zone located in the lower portion of an enclosing casing or housing 36 generally circular in cross-section about a vertical axis. The grinding elements include a circular series of grinding balls 38 which cooperate with upper and lower grinding rings 40 and 42 respectively to reduce the coal to the desired degree of fineness; the raw coal being delivered to the pulverizing chamber 44 above the level of the grinding rings by means of a known type of motor driven feeder 46 mounted on the pulverizer casing 36.

In this form of pulverizer, the lower grinding ring 42 is maintained stationary, being mounted on an annular support 48 integral with the base plate 50 which forms the bottom wall of the casing or housing 36. A conical wall 52 surrounding the lower grinding ring 42 and flaring upwardly toward the casing 36 serves to guide the incoming raw coal into the zone of action of the balls 38. The upper grinding ring 40, concentric with the lower grinding ring 42, is rotated about its central vertical axis to cause the balls 38 to roll relative to both grinding rings; the upper grinding ring 40 being driven by motor 30 operating through pinion shaft 54, gearing within the housing 36, a spider member 58, and a drive ring 60. Grinding pressure between the balls and rings is resiliently and adjustably maintained in the usual manner by means of circumferentially spaced springs 62 seated at their lower ends against the drive ring 60.

A bell shaped member 64, rotatable with the drive member 58 and constituting an integral extension thereof, terminates in a lower rim portion 66 of bulbous cross-section at a level corresponding to the reduced inner edge portion 68 of the lower grinding ring 42, thereby forming a relatively narrow annular passage or throat 70 through which carrier air is admitted to the grinding zone. The coal is fed to the region exteriorly of the circle of balls 38 and as the coal becomes pulverized, the particles are swept upwardly by the stream of carrier fluid admitted to the grinding zone through the throat 70, the majority of the pulverized particles being carried upwardly in the region interiorly of the circle and discharged laterally through a circumferential series of ports 72 in the drive ring 60. The finer

particles continue upwardly through the chamber 44 and are discharged from the pulverizer through the outlet 20, while the coarser particles drop out of the current and are returned to the pulverizing zone for further reduction. A plow 14 attached to the rotating grinding ring 40 serves to agitate the mass of coal to be pulverized so that the coal may move freely into the zone of action of the balls 38.

The extension member 64 is provided exteriorly with a series of circumferentially spaced vanes 76 adjacent its lower rim portion 66, such vanes being inclined to the vertical at an angle of about forty-five degrees, the direction of inclination being determined by the direction of rotation of the member 64 which for the structure illustrated will be understood to be counterclockwise, as indicated by the arrow in Fig. 3. Plow 78, diametrically arranged, are secured to the interior wall of the member 64 and extend downwardly for an appreciable distance below its bottom edge.

A multi-duct structure 80 adjacent the lower side of the base plate 50 provides separate ducts 82 and 84 for conducting fresh make-up air and the returning fuel-air mixture to the interior of the pulverizer 10. The air admitted through duct 82 may be heated or unheated, as desired, and the duct fitted with the usual regulating damper or dampers, a supply of heated air being suitably admitted through opening 82a under control of damper 83 and a supply of cooler tempering air being suitably admitted through a branch opening 82b under control of damper 85. The air inlet duct 82 is formed by circular pipe sections 86 and 88 joined in elbow relation to provide upward flow of air into the space 90 interiorly of the bell-shaped extension member 64; the section 88 extending vertically through the circular base plate opening 92 and terminating in an outlet 94 coaxial with the extension member 64 at an appreciable distance above the bottom rim portion 66; thereby defining an annular space 96 between the section 88 and the wall of the opening 92, and an annular space 98 between the section 88 and the rim portion 66 of member 64. A throat ring 100 integral with and surrounding the inlet pipe section 88 is formed with upper and lower conical deflecting surfaces 102 and 104 positioned below the throat passage 10, the purpose of such surfaces to be later defined. A stationary guide plate 106 extends from the perimeter of the base plate opening 92 to the top edge of the annular support 48 thereby providing an upwardly flaring conical surface 108 for directing the flow of air and fuel toward the throat passage 10.

The return duct 84 for the surplus pulverized coal and air mixture forms a continuation of the return length 28 of the main distributor conduit 24 to effect return of the fuel-air mixture to the annular space 96 which surrounds the pipe section 88 for admitting fresh make-up air. The duct 84 is of rectangular cross-section for the major portion of its length and, being inclined upwardly from its connection with the return pipe length 28, is fitted with a plug insert door 110 for inspection and cleaning. A transition is made in the horizontal width dimension of the duct 84 as it approaches the annular outlet space 96, the transition from the normal width dimension at location 112, for example, including diverging side wall portions 114 together with continuing curved wall portions 116 terminating adjacent the perimeter of the base plate opening 92. An annular flange 118 forms a top wall por-

tion of duct 84 and defines the perimeter of the duct outlet which registers with the outer diameter of the annular area 96. The bottom wall portion 120 of duct 84, from approximately the center line position 122, is inclined to the horizontal at a considerably greater angle than the general line of flow through the duct at preceding positions, the wall portion or bottom plate 120 being flat and extending upwardly to a position above the flange 118 to provide an inclined projecting lip 124 subtending an angle of approximately 60 to 75 degrees measured horizontally about the central axis of the annular outlet area 96, and having its peripheral edge circular as seen in horizontal projection.

In the operation of the system described, the air admitted to the pulverizer through duct 82 is discharged axially and upwardly into the space 90 interiorly of the spider extension 64. The direction of air flow is then reversed and the air caused to flow downwardly through the annular passage 98 formed between the inlet pipe section 88 and the rim 66 at the lower open end of the rotating member 64. The make-up air thus approaches the throat ring 100 from above and is deflected outwardly by the concave conical upper surface 102 of the ring toward the upwardly flaring surface 108 of the surrounding conical plate 106. The mixture of fuel and air returning from conduit 24 through duct 84 is admitted to the pulverizer through the annular opening 96 and thus approaches the throat ring 100 from below, the fluent mixture being deflected outwardly by the conical under surface 104 of the ring also toward the upward flaring surface 108 as in the case of the entering make-up air. As a result, the two streams are combined and thoroughly mingled to provide a single stream of substantially uniform density for flow into the pulverizing zone through the throat 10, the streams being mingled in a region immediately adjoining the throat where the velocities are maintained sufficiently high to prevent solids dropping out of suspension, thus obviating a possible interference with free circulation of the returning fuel by particles accumulating in the various ducts and passages. The circulation of fluid through the pulverizer is also assisted by the vanes 76 and plows 78 which keep the solids constantly in motion to prevent obstruction of the narrow annular passages 10 and 96 respectively.

I claim:

1. In a pulverizer having grinding elements in the lower portion of an enclosing housing, said housing having an outlet leading from its upper portion, said elements including a member formed with a grinding surface arranged annularly about a vertical axis between a material inlet circumference and a material outlet circumference disposed at different radial spacings from said axis, means for feeding material to be pulverized to a region adjacent said inlet circumference, means forming an annular throat adjacent said outlet circumference, means for causing air to flow through said throat for transporting particles of pulverized material to and through said outlet, means for admitting said air to said pulverizer in separate upwardly directed concentric streams of which an inner stream is composed of relatively clean air and an outer stream is composed of air in which pulverized material particles are suspended, said inner air stream being admitted to the interior of said housing at a level higher than the level of admission of said outer particle-suspending stream, means defining an annular

space in the region below and adjacent said throat, means for causing said streams to become mingled in said annular space to form a substantially homogeneous fluent mixture, and means for directing said mixture upwardly through said throat.

2. In an air swept pulverizer adapted for inclusion in a pulverized material circulating system wherein a fluent mixture of material and air is continuously discharged from said pulverizer and a portion of said mixture is continuously returned to said pulverizer, a portion of the mixture discharged from said pulverizer being continuously discharged from said system, means defining an annular grinding zone within the lower portion of the enclosing pulverizer housing, said means including a member having an upwardly facing grinding surface of annular formation about a vertical axis, means forming an annular throat adjacent the inner circumference of said grinding member, means for supplying air to said pulverizer to replace air discharged from said system comprising a pipe arranged coaxially with said throat and providing an outlet at its upper end in a zone centrally of and above said throat, means for returning a portion of the fluent mixture to said pulverizer in an upwardly directed annular stream surrounding said pipe, means for causing said air and said returned fluent mixture to become mingled in an annular zone below and adjacent said throat, and means for directing the resulting mixture upwardly through said throat.

3. In an air swept pulverizer adapted for inclusion in a pulverized material circulating system wherein a fluent mixture of material and air is continuously discharged from said pulverizer and a portion of said mixture is continuously returned to said pulverizer, a portion of the mixture discharged from said pulverizer being continuously discharged from said system, means defining an annular grinding zone within the lower portion of the enclosing pulverizer housing, said means including a member having an upwardly facing grinding surface of annular formation about a vertical axis, means forming an annular throat adjacent the inner circumference of said grinding member, means for supplying air to said pulverizer to replace air discharged from said system comprising a pipe arranged coaxially with said throat and providing an outlet at its upper end in a zone centrally of and above said throat, means for returning a portion of the fluent mixture to said pulverizer in an upwardly directed annular stream surrounding said pipe, means for causing said air and said returned fluent mixture to become mingled in an annular zone below and adjacent said throat, said last named means including surfaces formed annularly of said pipe for deflecting said air and said returned mixture outwardly toward said annular zone, and means for directing the resulting mixture upwardly through said throat.

4. In an air swept pulverizer adapted for inclusion in a closed circulating system of the type described, upper and lower grinding rings arranged coaxially within the lower portion of the pulverizer housing, a circular row of rollable grinding elements positioned intermediate said rings to define an annular pulverizing zone, means for rotating one of said rings and thereby causing said grinding elements to roll relative to both of said rings, an inverted cup-like member rotatable about the axis of said rings and extending downwardly into the space inwardly of said rings for defining an annular throat adja-

cent the inner periphery of said lower ring, means for supplying air to said pulverizer comprising a pipe extending upwardly into said member for delivering said air to the interior of said member at a level above said throat, means for reversing the direction of flow of said air to cause said air to flow downwardly in an annular stream surrounding said pipe, means for returning air containing pulverized material to said pulverizer in an annular stream in opposition to the downward flow of said first named stream of air, said returned material-laden air constituting a portion of the total discharge of air from said pulverizer, a deflector ring surrounding said pipe having oppositely inclined conical surfaces converging at a location below said throat for deflecting said annular streams outwardly in intersecting relation toward an annular zone below and adjacent said throat, thereby causing said separate streams to be mingled in said outer annular zone, and means for directing the resulting mixture from said mingling zone toward said throat.

5. In an air swept pulverizer adapted for inclusion in a closed circulating system of the type described, upper and lower grinding rings arranged coaxially within the lower portion of the pulverizer housing, a circular row of rollable grinding elements positioned intermediate said rings to define an annular pulverizing zone, means for rotating one of said rings and thereby causing said grinding elements to roll relative to both of said rings, an inverted cup-like member rotatable about the axis of said rings and extending downwardly into the space inwardly of said rings for defining an annular throat adjacent the inner periphery of said lower ring, means for supplying air to said pulverizer comprising a pipe extending upwardly into said member for delivering said air to the interior of said member at a level above said throat, means for reversing the direction of flow of said air to cause said air to flow downwardly in an annular stream surrounding said pipe, means for returning air containing pulverized material to said pulverizer in an annular stream in opposition to the downward flow of said first named stream of air, said returned material-laden air constituting a portion of the total discharge of air from said pulverizer, a deflector ring surrounding said pipe having oppositely inclined conical surfaces converging at a location below said throat for deflecting said annular streams outwardly in intersecting relation toward an annular zone below and adjacent said throat, thereby causing said separate streams to be mingled in said outer annular zone, and means including an upwardly flaring conical surface for directing the resulting mixture from said mingling zone into said throat, said surface defining the outer boundary of said mingling zone and terminating at the outer periphery of said annular throat.

6. In an air swept pulverizer adapted for inclusion in a circulation system such as described, means forming an annular grinding zone within the lower portion of the enclosing pulverizer housing, means including a downwardly expanding bell-shaped member for defining an annular throat adjacent the inner periphery of said grinding zone, said member terminating in a rounded lower rim portion forming the inner circumferential boundary of said throat, means for supplying fluid streams of different densities to said pulverizer for subsequent mingling and flow through said throat, means for admitting one of said

streams to the interior of said pulverizer comprising a pipe arranged centrally of said bell-shaped member and extending upwardly therein beyond the level of said lower rim portion and throat, means for admitting the other of said streams to the interior of said pulverizer annularly of said upwardly extending pipe, means for reversing the flow of said first named stream to form an annular stream flowing downwardly between said pipe and the interior wall of said bell-shaped member, a deflector ring contiguous to and surrounding said pipe having an upper and a lower conical surface inclined in opposite directions from adjacent said pipe and converging in an outer peripheral edge spaced from said pipe at a level intermediate said throat and the area of admission of said second named stream, said conical surfaces being so positioned in relation to the flow of said streams that said streams are deflected outwardly thereby in mixing relation into an annular zone below and closely adjacent said throat, and means for directing the resulting mixture upwardly through said throat.

7. In an air swept pulverizer adapted for inclusion in a circulation system such as described, means forming an annular grinding zone within the lower portion of the enclosing pulverizer housing, said means including a grinding ring having a grinding surface formed annularly about a vertical axis, a downwardly expanding bell-shaped member rotatable relative to said ring about said axis and terminating in a lower rim portion inwardly of said grinding ring to form an annular throat, means for supplying fluid streams of different densities to said pulverizer for subsequent mingling and flow through said throat, means for admitting each of said streams to the interior of said pulverizer in an upward direction, the area of admission for one of said streams being disposed centrally of said bell-shaped member at a level above said throat, the area of admission for the other of said streams being arranged annularly of said first named area at a level below said throat, means for directing said streams to a common annular zone below and adjacent said throat, said last named means including surfaces of annular formation arranged to deflect said streams outwardly in intersecting relation into said zone, means including an upwardly flaring conical wall forming the outer boundary of said annular zone for directing the resulting mixture upwardly toward said throat, and a circumferentially spaced series of inclined vanes on said rotatable bell-shaped member for maintaining said throat clear of obstructing material.

8. In an air swept pulverizer adapted for inclusion in a circulation system such as described, means forming an annular grinding zone within the lower portion of the enclosing pulverizer housing, said means including a grinding ring having a grinding surface formed annularly about a vertical axis, a downwardly expanding bell-shaped member rotatable relative to said ring about said axis and terminating in a lower rim portion inwardly of said grinding ring to form an annular throat, means for supplying fluid streams of different densities to said pulverizer for subsequent mingling and flow through said throat, means for admitting each of said streams to the interior of said pulverizer in an upward direction, the area of admission for one of said streams being disposed centrally of said bell-shaped member at a level above said throat, the area of admission for the other of said streams being

arranged annularly of said first named area at a level below said throat, means for directing said streams to a common annular zone below and adjacent said throat, said last named means including surfaces of annular formation arranged to deflect said streams outwardly in intersecting relation into said zone, means including an upwardly flaring conical wall forming the outer boundary of said annular zone for directing the resulting mixture upwardly toward said throat, a circumferentially spaced series of inclined vanes on said rotatable bell-shaped member for maintaining said throat clear of obstructing material, and a plow on said member extending downwardly into said annular mingling zone to the level of said annular deflecting surfaces.

9. In combination, an air swept pulverizer adapted for inclusion in a circulating system such as described, means forming an annular grinding zone within the lower portion of the pulverizer housing, means forming an annular throat adjacent a circumference of said grinding zone, means for admitting fluid streams of different densities to said pulverizer for subsequent mingling and upward flow through said throat, means forming openings concentrically arranged with respect to said vertical axis for admitting said streams to said pulverizer at vertically separated locations above and below the level of said throat, the lower of said openings being annular, means for conducting said fluid streams to said openings comprising a multi-duct structure having horizontally disposed conduit portions extending toward said vertical axis from diametrically opposite directions, an upright pipe section forming an elbow extension of one of said conduit portions and providing said fluid admission opening above the level of said throat, the other of said conduit portions being formed with side walls spaced from said upright pipe section and terminating adjacent the outer circumference of said annular fluid admission opening, said other conduit portion having an annular bottom wall portion surrounding said upright pipe section and extending upwardly at an inclination to said vertical axis, said annular bottom wall portion terminating in an inclined arcuate lip portion overlying a portion of the horizontally projected area of said annular opening to effect substantially uniform distribution of the entering fluid throughout the available entrance area, means for directing said separately admitted fluid streams to an annular zone below and adjacent said throat, and for causing said streams to be mingled substantially throughout said zone, and means for directing the resulting mixture upwardly from said zone into and through said throat.

10. In a pulverizer having grinding elements in the lower portion of an enclosing housing, said housing having an outlet leading from its upper portion, said elements including a member formed with a grinding surface arranged annularly about a vertical axis between a material inlet circumference and a material outlet circumference disposed at different radial spacings from said axis, means for feeding material to be pulverized to a region adjacent said inlet circumference, means forming an annular throat adjacent said outlet circumference, means for causing carrier fluid to flow through said throat for transporting particles of pulverized material to and through said outlet, means for admitting said carrier fluid to said pulverizer in separate upwardly directed concentric streams of which an inner stream is

of lower density than an outer stream, said inner stream being admitted to the interior of said housing at a level higher than the level of admission of said outer stream, means defining an annular space in the region below and adjacent to said throat, means for causing said streams to become mingled in said annular space to form a mixture thereof, and means for directing said mixture upwardly through said throat.
